UNITED STATES PATENT OFFICE.

CHARLES A. KETTERER, OF EAST ST. LOUIS, ILLINOIS.

REFRIGERATOR.

1,181,772.

Specification of Letters Patent.

Patented May 2, 1916.

Application filed October 26, 1914. Serial No. 868,785.

To all whom it may concern:

Be it known that I, CHARLES A. KETTERER, a citizen of the United States, and resident of East St. Louis, Illinois, have invented 5 certain new and useful Improvements in Refrigerators, of which the following is a specification containing a full, clear, and exact description, reference being had to the accompanying drawings, forming a part 10 hereof.

My invention relates to improvements in refrigerators, in which there is a single container for ice and salt through which there are extended open ended flues exposed to 15 the ice and salt and in which container there are openings in the outer walls thereof to provide for the overflow of the salt laden water from the ice.

The objects of my invention are, first; to 20 provide means whereby the outer surface of the ice and salt container is kept free from frost; second, to facilitate filling the container with ice by providing one container having flues therein; and third, to increase 25 the circulation of air within the refrigerator about the ice container.

The above and other objects are attained 30 by the structure illustrated in the accompanying drawings, in which—

Figure 1 shows in longitudinal, sectional elevation, a refrigerator of the "display case" type, embodying my improvements; and Fig. 2 is a sectional plan taken on the line 2—2 of Fig. 1.

Referring by numerals to the accompanying drawings, 3 designates the refrigerator body, which has extending therefrom one or more display cases 4. This refrigerator body and the display cases are both constructed with insulated walls of any approved design. By preference and as illustrated, the display cases have in their fronts glazed panels.

In order to provide for access to the display cases, there are hinged doors 5 in the rear of each case, and in order to provide for cleaning the refrigerator body and removing the ice container 6, there are the hinged doors 7 in the rear of the refrigerator body. For filling the container with ice and salt, I provide in the top of the refrigerator a hinged cover 8.

Each of the display cases is in open, direct communication with the refrigerator body, and in order to promote circulation 55 of air currents between the refrigerator

body and the display cases, I provide the deflectors comprising a horizontal partition 9 spaced from the upper wall of each display case and extending from the refrigerator body to a point approximately one-third the length of the display case, and a vertical partition 10 extending from the partition 9 to a point affording ample space for air circulation between the refrigerator 60 body and the display cases.

The ice container 6 is preferably constructed of sheet metal and of hopper shape, that is substantially rectangular in plan, and its end walls converging to a point 70 forming the inclined walls 11 in which openings are formed to receive the metallic flues 11^a. These flues are secured in the openings by means of flanges 12, and are held at their upper ends by rods 13 which extend from 75 one wall of the container to the other and through each flue.

14 designates a removable cover for the container which is provided with openings 15 registering with the flues, whereby to conserve ice by inclosing it against exposure, yet permit free circulation of air through 80 the flues. In the top of each flue I arrange a section of screen wire 16, in order to prevent ice dropping therethrough when filling 85 the container around the flues. At a point adjacent the inclined walls 11 I arrange a row of overflow openings 17, which extends around the entire container and each flue, and through which the salt laden water 90 from the container flows onto the outer surfaces of the container and flues for the purpose of preventing a collection of frost, thereby greatly adding to the efficiency of 95 the ice container.

In refrigerators of this type the ice and salt and the "brine" resultant therefrom reach a much lower temperature than the freezing point, and I find by keeping the outer surface of the container free from 100 frost the refrigerator reaches a much lower temperature. The container is provided with supporting legs 18, and for purposes of draining the container I provide a cock 19 in the bottom thereof.

20 designates a pan resting on the bottom of the refrigerator body, beneath the entire ice container, and is arranged to receive the salt laden water from the overflow openings 110 in the container and conduct it away from the refrigerator through the pipe 21.

In Fig. 1 I have shown arrows indicating

the course of air through the refrigerator body and display case.

It will be observed that the intake ends of the flues are considerably above the tops of the display cases and that the refrigerator body is of greater height than the display cases, whereby to draw the warm air constantly out of the display cases and direct it through the flues to the bottom of the refrigerator body and display cases. The partitions assist in the separation of the cold and warm currents of air.

Having thus described my invention, what I claim as new therein and desire to secure by Letters Patent of the United States is:—

1. In a refrigerator, a salt and ice container having a hopper shaped bottom, and open ended vertical tubes extended through the container and bottom, there being over-flow openings formed in the walls of said container and tubes, whereby salt laden water from the container flows over the outer surface of said hopper bottom and

over the inner faces of said tubes to prevent the collection of frost on said surfaces. 25

2. In combination with a refrigerator having means therein for causing air to circulate from its central portion outwardly along its bottom and thence inwardly along its top, a salt and ice container having a 30 hopper shaped bottom and open-ended vertical air tubes extended therethrough, a cover over the salt and ice container having openings therethrough registering with said air tubes and there being openings through the 35 walls of said container and tubes whereby salt laden water from the salt and ice container will flow over the surfaces of said container and air tubes.

In testimony whereof, I have signed my 40 name to this specification, in presence of two subscribing witnesses.

CHARLES A. KETTERER.
